UNITED STATES PATENT OFFICE.

ALEXANDER MUNROE AND FAYETTE F. FINK, OF OMAHA, NEBRASKA.

DESIGN FOR A NUMBER-DISPLAY CASING.

42,109.

Specification for Design.

Patented Jan. 23, 1912.

Application filed August 8, 1911. Serial No. 643,066. Term of patent 7 years.

To all whom it may concern:

Be it known that we, ALEXANDER MUNROE and FAYETTE F. FINK, citizens of the United States, residing at Omaha, in the county of Douglas and State of Nebraska, have invented a new, original, and ornamental Design for a Number-Display Casing, of which the following is a specification, reference being had to the accompanying drawing, forming a part thereof.

Figure 1 is a plan view of a number-display casing, showing our new design.

Fig. 2 is a rear view. Fig. 3 is a front view, and Fig. 4 is an end view of the same.

We claim:

The ornamental design for a number-display casing as shown.

In testimony whereof we have affixed our signatures in presence of two witnesses.

ALEXANDER MUNROE.
FAYETTE F. FINK.
